UNITED STATES PATENT OFFICE.

LEONHARD HEYDT, OF STRASBURG, ALSACE, GERMANY.

STEERING APPARATUS.

SPECIFICATION forming part of Letters Patent No. 313,733, dated March 10, 1885.

Application filed August 25, 1884. (No model.) Patented in Germany May 16, 1884, No. 30,276; in France August 12, 1884, and in England December 31, 1884, No. 17,101.

To all whom it may concern:

Be it known that I, LEONHARD HEYDT, a subject of the Emperor of Germany, residing at Strasburg, Alsace, Germany, have invented certain new and useful Improvements in Steering Apparatus, of which the following is a specification.

My invention relates to that class of steering apparatus for screw-steamers in which a cylindrical rudder is arranged around the propeller, the object of my invention being to so construct the rudder as to make the steering and turning of the vessel more rapid and easy than with rudders of this character as heretofore made.

In the accompanying drawings, Figure 1 is an outline view of the stern of a vessel with my improvement applied thereto. Fig. 2 is an end view of my improved rudder, showing the screw-propeller inside it. Fig. 3 is a side view of the stern of the vessel, showing the rudder in section; and Fig. 4 is a sectional plan of the rudder, showing the vessel in diagrammatic outline.

A is the screw-propeller, around which is the rudder B in the form of a hollow cylinder or tube open at both ends. This cylinder is provided with journals mounted in vertical

bearings, and the upper journal is prolonged into the stem D, through the medium of which 30 the rudder is turned on its axis formed by these journals. To the outside of this cylindrical rudder are fixed, in a vertical position, two tangential wings, C C, on opposite sides, these wings being of the concave outwardly-bent form shown in Fig. 3. When the rudder is turned one way or the other, as shown in Fig. 4, to steer the vessel, it will be observed that these wings present surfaces offering a more effective resistance to the water in steering than if the outside of the rudder were of the usual cylindrical form.

I claim as my invention—

The herein-described rudder for screw-propellers, said rudder consisting of a cylinder 45 having two bent tangential wings, C C, secured in a vertical position on opposite sides to the outer surface, substantially as set forth.

In testimony whereof I have signed my name to this specification in the presence of two subscribing witnesses.

LEONHARD HEYDT.
